No. 609,423.

Patented Aug. 23, 1898.

H. J. FAUST.
AXLE LUBRICATOR.

(Application filed Feb. 21, 1898.)

(No Model.)

FIG - 1 -

UNITED STATES PATENT OFFICE.

HENRY JENNINGS FAUST, OF DENMARK, SOUTH CAROLINA.

AXLE-LUBRICATOR.

SPECIFICATION forming part of Letters Patent No. 609,423, dated August 23, 1898.

Application filed February 21, 1898. Serial No. 671,162. (No model.)

To all whom it may concern:

Be it known that I, HENRY JENNINGS FAUST, a citizen of the United States, residing at Denmark, in the county of Barnwell and State 5 of South Carolina, have invented a new and useful Axle-Lubricator, of which the following is a specification.

The invention relates to improvements in axle-lubricators.

10 The object of the present invention is to improve the construction of axle-lubricators and to provide a simple, inexpensive, and efficient one which will enable the spindles of an axle to be easily and thoroughly lubricated without removing the wheels.

15 The invention consists in the construction and novel combination and arrangement of parts, as hereinafter fully described, illustrated in the accompanying drawings, and 20 pointed out in the claims hereto appended.

25 In the drawings, Figure 1 is a perspective view of a portion of an axle with a lubricator constructed in accordance with this invention. Fig. 2 is a longitudinal section view 25 of the same. Fig. 3 is a transverse sectional view. Fig. 4 is a detail horizontal sectional view. Fig. 5 is a plan view, the cover of the oil-receptacle being open.

30 Like numerals of reference designate corresponding parts in all the figures of the drawings.

35 1 designates an axle upon which is mounted an oil-receptacle 2, located adjacent to the inner end of a spindle 3 and provided with an integral extension or plate 4, interposed between the axle 1 and the axle-bed 5. The extension or plate 4, which is arranged horizontally on the upper face of the axle, forms a continuation of the bottom of the lubricant-receptacle 2, and the axle-clip 6, which secures 40 the axle and axle-bed together, serves as the fastening device for holding the lubricant-receptacle upon the axle.

45 The lubricant-receptacle 2, which is provided with a hinged lid 7, has a straight edge 8 at the outer side of its bottom to abut against a corresponding shoulder 9 of the axle. The lid 7, which is hinged at its inner edge, is provided with a spring-catch 10, depending 50 from the outer edge of the lid and engaging a shoulder or stop 11, formed on the exterior of the receptacle 2. The hinged cap excludes

dust from the receptacle, and the spring-catch prevents the lid from opening accidentally while a vehicle is traveling over a rough surface.

55 The lubricant is conveyed from the receptacle to a groove 12 in the upper face of the spindle through a tube 13, extending outward substantially horizontally from the bottom of the receptacle and passing through an opening or bore 14 of the shoulder or enlargement 1^a of the axle at the inner end of the spindle. The axle is provided at the shoulder or enlargement with an opening or perforation 15, 60 communicating with the groove and forming a vent for the passage of air to insure a free flow of the lubricant. This construction insures a thorough lubrication of the spindles, and oil may be supplied to an axle while a vehicle is traveling along a road without necessitating the removal of a wheel. The arrangement of the tube in the opening or bore of the axle assists in retaining the receptacle in place.

65 70 75 In order to prevent the tube 13 from becoming clogged at its outer end by hardened oil accumulating in the groove of the spindle, the device is provided with a spring-actuated rod 16, extending through the bore or opening of the tube from the outer end thereof to about the center of the oil-receptacle 2. The inner end of the rod is connected with a spring 17, disposed substantially vertically and having its upper end bent rearward and 80 secured to the inner face of the rear wall of the receptacle, near the top thereof.

85 90 95 The spring 17 is arranged to be engaged by a resilient arm 18, depending from the cover of the receptacle and adapted to force the spring rearward and draw the rod inward when the cover of the receptacle is closed, and as soon as the cover is opened the rod springs outward and projects beyond the outer end of the tube.

95 The invention has the following advantages: The axle-lubricator is exceedingly simple and inexpensive in construction. It is securely mounted upon the axle at a point adjacent to the inner end of the spindle, and it will enable the latter to be thoroughly and easily lubricated without removing the wheel. The device also prevents dust from entering the receptacle, and the lid cannot accidentally

open while a vehicle is traveling over a rough road-bed. The rod which reciprocates in the tube of the oil-receptacle prevents the device from becoming clogged with hardened oil of the spindle should the device run dry, and the rod is automatically reciprocated by the opening and closing of the lid of the receptacle.

Changes in the form, proportion, and minor details of construction may be resorted to without departing from the spirit or sacrificing any of the advantages of this invention.

What I claim is—

1. The combination of an axle provided in its spindle with a groove and having an opening extending through the shoulder or enlargement at the inner end of the spindle and registering with the groove to form a vent, said axle being provided at the inner edge of the shoulder or enlargement with a straight edge or face, an axle-bed, a clip embracing the axle and the axle-bed, an oil-receptacle mounted upon the axle and arranged between the straight face or edge of the enlargement or shoulder and the adjacent end of the axle-bed and provided with an arm or plate interposed between the latter and the axle, and a tube extending from the receptacle through the opening to the groove, substantially as described.

2. The combination with an axle, of an oil-receptacle mounted thereon and having a tube extending to the spindle, a longitudinally-

movable rod arranged within the tube, and a hinged cover provided with means for actuating the rod, whereby the latter will be automatically operated as the cover is opened and closed, substantially as described.

3. The combination with an axle, of a receptacle mounted thereon and provided with a tube extending to the spindle, a rod arranged within the tube and adapted to project therefrom, a spring arranged within the receptacle and connected with the rod, and an arm mounted on the cover of the receptacle and arranged to depress the spring and draw the rod inward when the cover is closed, whereby the rod will be caused to spring outward when the cover is opened, substantially as described.

4. The combination with an axle, of an oil-receptacle mounted thereon and having a tube extending to the spindle, a longitudinally-movable rod arranged within the tube, and a hinged cover provided with means for actuating the rod, whereby the latter will be operated automatically when the cover is opened and closed, said means being located wholly within the receptacle when the cover is closed, substantially as described.

In testimony that I claim the foregoing as my own I have hereto affixed my signature in the presence of two witnesses.

HENRY JENNINGS FAUST.
